Primary Examiner — Keith J Wilson(74) *Attorney, Agent, or Firm* — Foundation Law Group LLP(57) **CLAIM**

We claim the ornamental design for a filter rack, as shown and described.

DESCRIPTION

FIG. 1 is a front, top perspective view, showing our new design for a filter rack;

FIG. 2 is a bottom, rear perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines show portions of the filter rack that form no part of the claimed design.

1 Claim, 8 Drawing Sheets(56)
